SLIDING CAR DOOR

Wilfred A. Beauchamp, Chicago, Ill., assignor, by
mesne assignments, to The Youngstown Steel
Door Company, Cleveland, Ohio, a corporation
of Ohio

Application June 9, 1933, Serial No. 675,005

14 Claims. (Cl. 20—22)

This invention relates to sliding doors for railway house cars.

It is an object of this invention to provide sliding car doors which shall be free of hangers or other rolling fixtures and be capable of being frictionally supported or disposed upon rolling means for movement toward open and closed positions.

A further object is to provide sliding doors for railway house cars having normal frictional engagement upon said cars and means carrying rolling devices associated with but independent of said doors for releasing such engagement and supporting said doors for antifrictional movement.

A further object is to provide sliding doors which shall be frictionally supported in their normal closed positions and means associated therewith for elevating said doors above their frictional support and exerting a positive force to said doors to impart opening movement thereto.

A further object is to provide sliding doors which shall be supported for movement upon antifriction means capable of engaging said means in the closing movement to effect automatic lowering movement of the doors and establish frictional engagement thereof with supporting means.

A further object is to provide railway house cars having sliding doors and carrying rolling means adapted to be projected to support said doors for antifrictional movement and to be retracted to cause frictional engagement between the doors and supports fixed to said cars.

Other objects of the invention will become clear as the description thereof proceeds.

In the drawings forming part of this specification

40 Figure 1 is a fragmentary elevation of the side of a railway house car upon which the invention is utilized, a sliding door mounted upon said side being shown in closed position;

45 Figure 2 is a view similar to Figure 1, the door being shown in partly open position;

Figure 3 is a fragmentary elevation on an enlarged scale of a portion of the structure embodying the invention shown in Figure 1;

50 Figure 4 is a vertical section taken on line 4—4 of Figure 3;

Figure 5 is a horizontal section taken on line 5—5 of Figure 3;

55 Figure 6 is an elevation of a modified form of the invention;

Figure 7 is a vertical section taken on line 7—7 of Figure 6; and

Figure 8 is a plan view of the structure shown in Figure 6.

Referring to the drawings and more particularly to the embodiment of the invention illustrated in Figures 1 to 5, inclusive, the numeral 10 designates a portion of a side of a railway house car upon which is mounted for sliding movement a door 11 adapted to close the door opening 12 provided in the car side. Said door may be of any preferred construction and, as illustrated, comprises a metallic panel 13 formed with a plurality of horizontally extending corrugations 14 which merge at their ends with vertical corrugations 15 and 16 provided in the metallic panel inwardly of the vertical edges of the door. The metallic panel 13 is suitably reinforced at the vertical and horizontal margins thereof, the reinforcement for the lower horizontal margin preferably taking the form of a Z-bar 17 disposed with its web 18 substantially horizontally and with its oppositely extending flanges 19 and 20 positioned in spaced vertical planes. The flange 19 is positioned between the lower margin of the panel 13 and a backing plate 21 and secured to said panel and backing plate as by rivets 22. In its closed position the door is adapted to be locked to the side 10 of the railway house car by means of a locking mechanism indicated generally by the numeral 23. The opening movement of the door is limited by means of the stop member 24 carried preferably by the car side 10.

The construction of the side 10 of the railway house car may include an angle side sill 25 positioned with one leg 26 extending upwardly. This leg within the door opening 12 is coped as indicated at 27 and a threshold plate 28 disposed upon the floor 29 within the door opening 12 extends outwardly from said opening into proximity with the inner face of the door and is supported beyond said opening by means of an angle member 30 secured to the leg 26 of the side sill. The sill 25 is preferably reinforced by means of a channel member 31 which, if desired, may extend the entire length of the car. The web 32 of the reinforcing channel member 31 has secured thereto a plurality of spaced brackets 33 adapted, as clearly shown in Figures 1 and 4 of the drawings to frictionally engage the horizontally disposed web 18 of the Z-bar reinforcing member 17 secured to the door so as to provide frictional support for said door in its normal or lowered position.

It will be apparent that in the normal or lowered position of the door 11 the frictional engagement thereof with the brackets 33 will prevent or at least retard sliding movement of the door in any position thereof between closed and full open positions. Means has been provided whereby when it is desired to move the door said door may be supported upon antifriction means so as to enhance the ease of movement thereof.

10 To this end each of the brackets 33 is provided with mechanism whereby the door may be elevated so as to break the frictional engagement thereof with the brackets and be disposed upon antifriction means for sliding movement.

15 Each of the brackets illustrated in Figures 1 to 5, inclusive, comprises a body portion 34 secured to the web 32 of the channel reinforcing member 31 as by means of rivets 35. The body portion 34 of each of the brackets is provided with

20 a bearing 36 and outwardly extending spaced vertically disposed flanges 37 and 38. At their outer ends these flanges are formed so as to provide portions 39 and 40 extending substantially parallel to the web 32 and to which the cover member 41 of the brackets 33 is adapted to be secured as by means of rivets 42. These rivets, as clearly shown in Figure 5 of the drawings, are disposed in spaced relation to the web 32 of the channel reinforcing member whereby removal of the cover member 41 may be had for the purpose of repair or replacement of the mechanism hereinafter described carried by the brackets without disturbing the relationship of the door upon the car side. The cover member 35 41 is provided with a bearing 43 disposed in horizontal alignment with the bearing 36 formed in the body portion of the bracket.

Each of the brackets 33 carries mechanism adapted to elevate and support the door for antifrictional movement. This mechanism comprises a roller retainer 44 provided with oppositely extending trunnions 45 and 46 journaled in the bearings 36 and 43 provided, respectively, in the body portion and in the cover member of the brackets 33. As clearly shown in Figure 3 of the drawings, the trunnions 45 and 46 are disposed intermediate the ends of the roller retainer. A roller 47 is mounted upon the upper end of each of the roller retainers 44, each of said rollers preferably being provided with roller bearings 48. The lower ends of each of the retainers 44 are connected by means of an actuating bar 49 whereby simultaneous operation of the mechanism above referred to may be had. This connection, as more clearly illustrated in Figures 3 and 4 of the drawings, may be effected by means of lugs 50 formed preferably integral with said retainers, said lugs extending through openings formed at proper intervals in flattened portions 51 of the hollow actuating bar 49. It will be apparent, particularly from the showing of Figure 4 of the drawings, that the lugs 50 and the actuating bar 49 are positioned in proximity to the reinforcing member 31. This relationship affords protection for the actuating bar and prevents accidental disengagement thereof from the lugs. An operating lever 52 conveniently mounted upon the channel reinforcing member 31 may be utilized to impart movement to the connecting bar 49 70 to affect operation of the roller retainers. The lever 52 may be pivotally connected, as indicated at 53, to one end of the actuating bar.

The roller retainers 44, with the exception of the first retainer, that is, the one adjacent the forward margin of the door opening, are identi-

cal in construction. The retainer which is secured adjacent the forward margin of the door opening, however, is provided additionally with an inwardly extending projection 54 adapted, during the elevation of the door by means of the hereinbefore described mechanism, to engage a shoulder 55 which may be provided by coping the downwardly extending vertical flange 20 of the Z-bar reinforcing member 17 as indicated at 56.

A somewhat modified form of bracket and roller retainer structure is illustrated in Figures 6 to 8, inclusive. The bracket 57 shown in these figures of the drawings is a one-piece bracket provided with aligned vertically extending grooves 58 and 59, the upper ends of which are open as indicated at 60 and the lower ends of which are closed in order to provide bearings 61 and 62, respectively. A roller retainer 63 may be assembled with the bracket 57 by downward movement of said retainer in said bracket. The retainer 63 is provided intermediate its ends with aligned trunnions 64 and 65 which in the assembly of the retainer with the bracket are inserted into the open ends of the grooves 58 and 59 and moved downwardly in said brackets until the trunnions are supported in the bearings 61 and 62 of the brackets. The upper end of the roller retainer 63 carries a roller 66 while the lower end of said retainer is provided with spaced flanges 67 and 68 between which the actuating bar 49 is disposed for connection to a plurality of such retainers by means of rivets such as 69 extending through the flanges 67 and 68 and apertures provided in the flattened portions 51 of said bar. The roller retainer 63, which is to be positioned adjacent the forward margin of the door opening, is provided with an inwardly extending projection 70 as in the case of the previously described embodiment of the invention.

While two forms of the invention have been illustrated it will be apparent that the following operation is applicable to both of these forms. To move the door from its closed position illustrated in Figure 1 of the drawings toward open position the locking mechanism 23 is released. The lever 52 is then grasped and moved in a clockwise direction as viewed in Figure 1 so as to exert a pull toward the left upon the actuating bar 49. The movement thus imparted to said bar is in turn effective to cause swinging movement of the roller retainers whereupon the rollers are projected beyond the brackets through openings provided therein into engagement with the web 18 of the Z-shaped reinforcing member 17 and the door 11 is elevated upon said rollers. It will be apparent from Figure 2 of the drawings, in which the door is shown in its elevated position, that the axis of the rollers will lie slightly to the right, as viewed in this figure, of the center of the trunnions provided on the roller retainers. In view of this relationship it will be apparent that subsequent to elevation of the door it may be moved to any desired position without further attention being paid to the elevating mechanism. The door may readily be again disposed in frictional engagement with the brackets by operation of the lever 52 in a counterclockwise direction. If the door is accidentally left in open position upon the rollers this result may also be obtained by the jarring of the car.

As hereinbefore explained the first roller retainer carries an inwardly extending projection. This projection is disposed in such relationship with the abutment provided on the Z-bar rein-

forcing member that during the latter part of the swinging movement of the retainer the projection will engage said abutment so as to impart opening movement to the door. Similarly as the door is moved toward closed position said abutment will engage said lug in the final closing movement of the door so that the retainers will automatically be swung so as to retract the rollers within the brackets, causing the door to be lowered into frictional engagement with said brackets. It will be evident in view of the swinging movement of the roller retainers that a horizontal displacement will be imparted to the rollers so that the door will be carried forward in the lowering movement thereof to insure closing of the door.

It is apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car, in combination, a sliding door, a plurality of spaced brackets secured to said car adapted to frictionally support said door, a roller retainer journaled intermediate its ends to each of said brackets, a roller carried by and extending beyond one end of each retainer, a connecting bar pivotally secured adjacent the opposite end of each retainer and means for actuating said bar to project said rollers beyond said brackets to elevate said door.

2. In a railway house car, in combination, a sliding door, a plurality of spaced brackets secured to said car adapted to frictionally support said door, a roller retainer journaled intermediate its ends to each of said brackets, a roller carried by and extending beyond one end of each retainer, a connecting bar pivotally secured adjacent the opposite end of each retainer and means for actuating said bar to project said rollers beyond said brackets to elevate said door, and means provided on one of said retainers engageable with said door during elevation thereof to impart initial opening movement thereto.

3. In a railway house car, in combination, a side sill, a sliding door, a plurality of brackets secured to said sill adapted to frictionally support said door, a roller retainer journaled intermediate its ends to each of said brackets, a roller carried by and extending beyond one end of each retainer, a connecting bar pivotally secured adjacent the opposite end of each retainer and means for actuating said bar to project said rollers beyond said brackets to elevate said door, said bar being disposed in proximity to said sill for the purpose set forth.

4. In a railway house car, in combination, a sliding door, a plurality of spaced brackets secured to said car adapted to frictionally support said door, means including rollers carried by said brackets adapted to engage and elevate said door, said rollers being maintained in door engaging position during movement of said door thereon, said means being actuated by said door in the final closing movement thereof to effect disengagement between said rollers and said door for the purpose set forth.

5. In a railway house car, in combination, a sliding door, a plurality of spaced brackets secured to said car adapted to frictionally support said door, means including rollers journaled in said brackets adapted to engage and elevate said

door, said rollers being disposed slightly beyond the centers of the journals to maintain the door in elevated position, said door in the final closing movement thereof disengaging said means from said door for the purpose set forth. 5

6. In a railway house car, in combination, a sliding door, a plurality of spaced brackets secured to said car adapted to frictionally support said door, means carried by said brackets adapted to engage and elevate said door and means provided on said first mentioned means for engaging and imparting initial opening movement to said door, said door in the final closing movement thereof engaging said second mentioned means to impart lowering movement to said first mentioned means for the purpose set forth. 10 15

7. In a railway house car, a sliding door, spaced brackets secured to said car adapted to frictionally support said door in its normal position, spaced grooves provided in each bracket, the upper ends of said grooves being open and the lower ends thereof being closed to provide bearings, a roller retainer for each bracket having oppositely extending trunnions intermediate its ends journaled in said bearings, a roller mounted upon the upper end of each retainer disposed within its bracket in the normal position of said door, a bar connecting said retainers for simultaneous movement and means for actuating said bar to project said rollers beyond said brackets 25 30 to elevate said door.

8. In a railway house car, a sliding door, spaced brackets secured to said car adapted to frictionally support said door in its normal position, spaced grooves provided in each bracket, the upper ends of said grooves being open and the lower ends thereof being closed to provide bearings, a roller retainer for each bracket having oppositely extending trunnions intermediate its ends adapted to be journaled in said bearings, 35 40 said retainers being disposed in said brackets by insertion through the open ends of said grooves.

9. In a railway house car, a sliding door, spaced one-piece brackets secured to said car adapted to frictionally support said door in its normal position, spaced grooves provided in each bracket, the upper ends of said grooves being open and the lower ends thereof being closed to provide bearings, a roller retainer for each bracket having oppositely extending trunnions intermediate 45 50 55 its ends journaled in said bearings, a roller mounted upon the upper end of each retainer disposed within its bracket in the normal position of said door, a bar connecting said retainers for simultaneous movement and means for actuating said bar to project said rollers beyond said brackets to elevate said door.

10. In a railway house car, in combination, a sliding door, a plurality of spaced brackets secured to said car adapted to frictionally support 60 65 said door, rolling means carried by said brackets, said rolling means being retracted within said brackets when the latter frictionally support said door, and means for projecting said rolling means beyond said brackets into engagement with said door for elevating said door.

11. In a railway house car, in combination, a sliding door, a plurality of spaced brackets secured to said car adapted to frictionally support said door, rolling means carried by said brackets, and longitudinally movable means for projecting said rolling means into engagement with said door for elevating said door. 70

12. In a railway house car, in combination, a sliding door, a plurality of spaced brackets se- 75

cured to said car adapted to frictionally support said door, a roller for each of said brackets, means journaled in each bracket and carrying said rollers, a member directly connecting said means for simultaneous movement, and lever means for actuating said member for the purpose set forth.

13. In a railway house car, in combination, a sliding door, a plurality of spaced brackets secured to said car adapted to frictionally support said door, a roller for each of said brackets, means journaled in each bracket and carrying said rollers, a member directly connecting said means for simultaneous movement, and lever

means for actuating said member for the purpose set forth, said member being disposed in proximity to said car to prevent damage thereto.

14. In a railway house car, in combination, a sliding door, a plurality of spaced brackets secured to said car adapted to frictionally support said door, a roller for each of said brackets, means journaled in each bracket and carrying said rollers, a longitudinally movable member directly connecting said means for simultaneous movement and lever means for actuating said member for the purpose set forth.

WILFRED A. BEAUCHAMP.
